UNITED STATES PATENT OFFICE.

HENRY H. FISHER AND WILLIAM C. BARNES, OF EVANSVILLE, INDIANA.

TROLLEY-REPLACER.

1,190,534.

Specification of Letters Patent. Patented July 11, 1916.

Application filed September 13, 1915. Serial No. 50,445.

To all whom it may concern:

Be it known that we, HENRY H. FISHER and WILLIAM C. BARNES, citizens of the United States, residing at Evansville, in the 5 county of Vanderburg and State of Indiana, have invented certain new and useful Improvements in Trolley-Replacers; and we do declare the following to be a full, clear, and exact description of the invention, such as 10 will enable others skilled in the art to which it appertains to make and use the same.

This invention relates to trolley replacers, particularly to that type which employs the feed wire for actuating the device, and 15 has for its object to provide a simple and inexpensive replacer of this type to effectively carry out the purpose for which it is designed.

Another object is to provide a replacer 20 which is practically automatic in its operation.

A still further object is to provide a replacer in the form of a movable carriage 25 slidable on the outer end of the trolley pole.

With these and minor objects in view, our 30 device consists of certain novel features of construction, combination and arrangement of parts which will hereinafter be more particularly described and claimed and shown in the drawings wherein:

Figure 1 represents a side elevation of our improved trolley replacer showing the movable carriage in retracted position; Fig. 2 is a similar view showing the carriage in 35 extended position; Fig. 3 is a top plan view of this improved device; Fig. 4 is a bottom plan view thereof; Fig. 5 is a central vertical longitudinal section through the replacer in position on the outer end of the trolley 40 pole; Fig. 6 is an end view; and Figs. 7 and 8 are transverse sections taken respectively on the line 7—7 and 8—8 of Fig. 1.

In the accompanying drawings in which 45 similar reference characters designate corresponding parts throughout the several views, 1 indicates a trolley pole having its outer end substantially squared as shown at 2, said pole being also provided on its outer end with the usual trolley 3 which is adapted to underlie the feed wire F. On this squared end of the trolley pole is a housing 4 in the form of a carriage slidable toward and away from said trolley 3. This housing 4 comprises side plates 5 whose outer 55 ends are provided with alined ears 6 having

bearings formed therethrough, while integrally joined with these side plates is a top plate 7. A flat bottom plate 8 is joined to the lower edges of the side plates 5 and is provided at its lower end with a suitable 60 hook or other fastening device 9 for securing one end of a contracting spring 10 to said housing or carriage. This contracting spring 10 is secured by its opposite end to the outer end of the trolley pole adjacent 65

said trolley. From this description, it is evident that this carriage 4 will move toward the trolley 3 unless it is held against the tension of the spring 10. In order to hold this carriage in retracted position 70 against the tension of the said spring, we have provided a catch 11 in the form of a hook-like member which coacts with a similar catch 12 on the lower end of the top carriage plate 7. This catch 11 is pivoted 75 at its lower end as at 13 and is provided with a leaf spring 14 for holding it in operative position. A pair of alined bearing ears 15 formed in the upper side of this housing 4 about midway its ends are provided with alined bearings therethrough. 80

A suitable trip member 16 in the form of a lever fulcrumed intermediate its ends between said ears 15, is used for actuating the catch 11. The lower end of this trip

member 16 is beveled as shown at 17 to engage the beveled portion 18 of the aforesaid catch member 11. The outer end of this trip 85 16 is provided with a pair of ears 19 between which a feed wire engaging roller 20 is adapted to revolve, while beneath the under side of said trip is positioned a V-shaped leaf spring 21 adapted to normally force the upper end of said trip away from the carriage member. For coaction with the ears 6 formed on the outer 90 end of said plates of the housing, we provide the bearing plates 22 which have their lower ends secured to the said plates of said housing and their upper ends bent laterally and then extended forwardly to provide bearing ears 23 whose bearings aline with the bearings of the aforesaid ears 6. Between each pair of bearing ears 6 and 23 95 is mounted to revolve therein a suitable feed wire guiding roller 24. These rollers 24 have downwardly and inwardly inclining edges for guiding said feed wire F into contact with the trolley 3. The aforementioned feed wire engaging roller 20 is preferably of 100

105 feed wire engaging roller 20 is preferably of 110

a length equal to the width between the outer sides of the guiding rollers 24. A cable 25 has one end secured to the hook 9 and extends through a suitable guide 26 formed on the trolley pole 1 and is adapted for returning the carriage 4 to its retracted position when the feed wire has been replaced on the trolley 3.

In normal operation, the parts of our improved replacer are positioned as illustrated in Fig. 1 of the accompanying drawings, the trolley pole being extended upwardly at an angle and having its trolley engaging the feed wire F. However, when said feed wire F is disengaged from the trolley 3, the outer end of the trolley pole 1 will tend to fly upwardly under the tension of the usual spring, not shown, provided at the junction of the trolley pole with the top of the car for causing such upward movement. This operation will cause the feed wire engaging roller 20 to strike the feed wire, thereby releasing the catch member 11 and causing the carriage to move toward the trolley under the tension of the spring 10. The feed wire F will then force the upper end of the trip member downwardly and be guided by the rollers 24 on the trolley 3. After this operation has taken place, electric current will again travel from the feed wire to the trolley pole and the carriage can then be returned to its retracted position by pulling on the cable 25, and the replacer will then be in position to again restore the trolley to the wire, should it leave the same.

From the foregoing description, the construction of our improved trolley replacer, the manner of applying the same to use, and the advantages thereof, will be readily understood and it will be seen that we have provided a simple and inexpensive, and efficient means for carrying out the objects of our invention.

Although we have particularly described the elements best adapted to perform the functions set forth, it is obvious that various changes in form, proportion and in the minor details of construction may be resorted to within the scope of the appended claims without departing from the spirit or sacrificing any of the principles of the invention.

Having described our invention, what we claim is:

1. The combination with a pole having a trolley, of a replacing device slidable thereon, means for retaining said device in retracted position, means for projecting said device into operative position, and means mounted on said device to release the same when struck by the feed wire.

2. The combination with a pole having a trolley, of a replacing device comprising a carriage slidable on said pole, means for retaining said carriage in retracted position,

means for projecting said carriage into operative position, and means on said carriage operable by the feed wire for releasing the same.

3. The combination with a pole having a trolley, of a replacing device comprising a carriage slidable on said pole, means for retaining said carriage in retracted position, means for projecting said carriage into operative position, and a trip mounted on said carriage and operable by the feed wire for releasing the same.

4. The combination with a pole having a trolley, of a replacing device comprising a carriage slidable on said pole, means for retaining said carriage in retracted position, means for projecting said carriage into operative position, and a swinging trip pivoted on said carriage adapted to release the same when struck by the feed wire.

5. The combination with a pole having a trolley, of a replacing device comprising a carriage slidable on said pole toward and away from said trolley, a catch for coaction with said carriage to retain the same in retracted position, a spring for projecting said carriage toward said trolley, and means pivoted on said carriage and operable by the feed wire for releasing the same.

6. The combination of a pole having a trolley, with a replacing device comprising a carriage slidable on said pole, a spring retracted trip pivoted on said carriage, a feed wire engaging means carried by the upper end of said trip, a catch for retaining said carriage in retracted position and adapted to be released by the trip when said trip is actuated by the feed wire, and a spring for projecting said carriage toward said trolley.

7. The combination of a pole having a trolley, with a replacing device comprising a carriage slidable on said pole, a feed wire guide carried by the outer end of said carriage, a catch for retaining said carriage in retracted position, a trip for actuating said catch, and a spring for projecting said carriage toward said trolley.

8. The combination of a pole having a trolley with a replacing device comprising a carriage slidable on said pole, a pair of spaced feed wire guides having downwardly and inwardly inclined edges secured to the upper end of said carriage, a catch for retaining said carriage in retracted position, a trip for actuating said catch, and a spring for projecting said carriage toward said trolley.

9. The combination with a pole having a trolley with a replacing device comprising a carriage slidable on said pole, a pair of spaced feed wire guide rollers having downwardly and inwardly inclined edges secured to the upper end of said carriage, a catch for retaining said carriage in retracted position, a trip for actuating said catch, a spring for

projecting said carriage toward said trolley, and means for returning said device to retracted position.

10. The combination with a pole having a substantially squared end, a trolley on the outer end of said pole, of a replacing device comprising a substantially squared housing surrounding said squared end and slidable thereon, a feed wire guide on the outer end 5 of said housing, a catch for retaining said carriage in retracted position, a trip for actuating said catch, a spring for projecting said housing toward said trolley, and means for returning said device to retracted position.
15. 11. The combination of a pole having a trolley with a replacing device comprising a carriage slidable on said pole, a pair of

spaced feed wire guide rollers secured to the outer end of said carriage, a trip pivoted to the upper side of the said carriage, a feed wire engaging roller of a length equal that of a pair of guide rollers carried by the upper end of said trip, a catch for retaining said carriage in retracted position adapted to be released by the trip when said trip is actuated by the feed wire, and a spring for projecting said carriage toward said trolley.

In testimony whereof we have hereunto set our hands in presence of two subscribing witnesses.

HENRY H. FISHER.
WILLIAM C. BARNES.
